UNITED STATES PATENT OFFICE.

JOHAN KARL KRISTIAN ANDERSEN, OF BROOKLYN, NEW YORK.

CHANGEABLE-LETTER DEVICE.

Application filed May 7, 1927. Serial No. 189,595.

The object of my present invention is the provision of a peculiar and advantageous changeable letter device, adapted to be used for stamping or printing purposes, or as an educational device.

With the foregoing in mind, the invention in all of its details will be fully understood from the following description and claims, when the same are read in connection with the drawing, accompanying and forming a part of this specification, in which:

Figure 1 is a fragmentary side elevation of the device, constituting the preferred embodiment of my invention.

Figure 2 is an end elevation of the same.

Figure 3 is a cross section of the device.

Figure 4 is a fragmentary longitudinal section of the device.

Similar numerals of reference describe corresponding parts in all of the views in the drawings.

Among other elements, my novel device comprises a plurality of endless flexible bands 1 arranged side by side and each provided at intervals in its length and on its outer sides with projections 2, bearing on their faces letters, as shown, numerals or other characters which are preferably produced by embossing on the faces of the projections.

The said device also comprises a plurality of side by side toothed discs 3, the discs 3 being arranged so that their teeth are adapted to enter the spaces between the projections 2 on the endless band 1. Each disc 3 is capable of being turned independently of every other disc, and from this it follows that each band 1 is adapted to be moved independently of every other band, and the projections 2 being provided on their faces with different letters or with different numerals or other characters, it follows that my adjustment of a series of the bands 1 or of all of the bands 1 various combinations of letters or other numerals or other characters may be produced in an exposed line as will be hereinafter understood. I would also have it understood, at this point, that the teeth of the disc 3 afford a means whereby the disc may be readily turned by the application of the fingers of the operator to the disc.

The bands 1 are mounted on and movable about a cylinder 4, and a guide member 5, the outer surface of the guide member 5 be-

ing convexed in cross section as clearly appears in Figure 3.

The discs 3 are loosely mounted on a shaft 6 disposed longitudinally of the device, and by reference to Figure 4 it will be noted that spacing washers 7 are mounted on the shaft 6 and are interposed between the discs 3 as to maintain the said discs 3 in spaced relation.

The casing of my novel device is of familiar and advantageous construction as will be appreciated when it is stated that the casing is made up of end walls 8, a top wall 9 interposed between and joining the end walls 8, and side walls 10, all of the said walls being preferably, though not necessarily, formed of sheet metal of appropriate thickness. The shaft 6 is mounted in the end walls 8, and the cylinder 4 is also interposed between and mounted in and supported by said end walls 8. The guide member 5 is interposed between the said end walls 8 and is provided at its ends with bendable tongues 9*, which are inserted through apertures in the end walls 8 and are bent against the outer sides of the end walls 8 so as to effect a connection between the guide member 5 and the said end walls 8.

The top wall 9 is of concavo-convex shape in cross section and the side walls 10 are provided with arms 11, which are pivotally connected to the extended portions of the shaft 6.

By virtue of the said construction, the side walls 10 swung from the full line position shown in Figure 2 to the dotted line positions shown in said figure and manifestly when the side walls 10 are in the dotted line positions, the endless bands 1 will be released, by the side walls 10, and therefore by manipulating the disc 3, the operator is enabled to adjust the band 1, so as to arrange the characters that appear in the exposed line. The exposed line of characters to be displayed are to be used for printing or stamping purposes and is disposed between the lower edge portion of the side walls 10, the said edge portions being deflected inwardly so as to rest normally at opposite sides of the row of projections 2, and in that way preclude casual movement of the endless bands 1. It will also be noted, in this connection, that when the side walls 10 are swung to the dotted line position shown in Figure 2, the row of projections 2 alluded to will be released from the side walls 10 so that the said walls 10

will offer no interference with the endwise adjustment of any one of the bands 1.

The side walls 10 are provided, on their end edges with clips 12, these clips 12 being designated when the walls are in their full line position shown in Figure 2, to frictionally or otherwise detachably engage the end walls 8, so as to detachably maintain the walls 10 in working relation. Manifestly, when a little stress is applied to either of the walls 10, the same may be swung from the full line position into the dotted line position shown in Figure 2.

It will be apparent from the foregoing, that my novel device is adapted to be used to advantage as an educational device, different combinations of letters, numerals or other characters being displayed by the row of projections 2 below the guide member 5 and between the free edge portions of the side walls 10. It will also be understood that the exposed row of projections 2 may be used in the conventional manner for stamping or printing purposes.

Notwithstanding the practical advantages ascribed to my novel device, it will be noted that the device is simple and inexpensive in construction, and in general is well adapted to withstand the usage to which devices of corresponding character are ordinarily subjected.

I have entered into a detailed description of the construction and relative arrangement of the parts in the present and preferred embodiment of my invention in order to impart a full, clear and exact understanding of the said embodiment.

I do not desire, however, to be understood as limiting myself to the construction disclosed, my invention being defined by my appended claims within the scope of which modifications may be made, without departure from my invention.

What is claimed is:

1. In a changeable device, in combination, a shaft, a plurality of toothed discs mounted loosely on said shaft, spacing means on the shaft and between the discs, a cylinder in parallelism with the shaft, 50 a guide member spaced from the cylin-

der and convexed on its outer side, a plurality of side by side endless flexible bands on said cylinder and guide member and each having a plurality of spaced projections adapted to cooperate with the teeth of a disc and to bear letters, numerals, or other characters, and a casing comprising a top wall concavo-convex in cross section, end walls supporting said shaft, cylinder and guide member, and side walls having arms pivotally connected to said shaft and also having means for detachably holding them to the end walls and further having inwardly directed edge portions adapted to rest at opposite sides of a row of projections on the endless band to expose said projections and to cooperate with the projections in preventing casual movement of the bands, one of the side walls when swung to open position affording access to the toothed disc for adjustment purposes.

2. A changeable device having side by side endless bands provided with spaced projections, means supporting said bands, toothed discs arranged to cooperate with the spaced projections for the adjustment of the bands, and a casing having walls arranged in one position to hold the bands against casual movement and to expose a row of projections and also adapted in another position to release the band and to afford access to the discs for the adjustment of the band.

3. A changeable device comprising appropriately supported endless bands arranged side by side and provided with character bearing portions, individual devices for cooperating with the bands for the independent adjustment of each band, and a casing enclosing the band and adjusting devices, said casing when closed operating to expose a row of characters of the band, while covering the remainder of the characters and also operating when closed to prevent casual movement of the bands, said casing adapted when open to release the bands and to afford access to the adjusting devices by the manipulation of the latter.

In testimony whereof I affix my signature.

JOHAN KARL KRISTIAN ANDERSEN.
